UNITED STATES PATENT OFFICE

2,200,058

ARTICULATOR

Edward L. Chott, Chicago, Ill.

Application May 15, 1937, Serial No. 142,790

8 Claims. (Cl. 32—32)

This invention relates to the art of denture and reconstruction or dental surveying, and more especially to improvements in articulators in this art. Articulators are well known in the art of dental surveying and reconstruction, and of primary importance in the construction of an articulator is maximum adjustability and accuracy and other features whereby the articulator approximates as closely as possible the jaw of the human mouth formation and articulated movement of the lower jaw.

It is now clearly established that the biting areas of the teeth, taken together, lie along a plane which is the curve of a sphere having a radius of four inches and is known as the occlusal plane. This plane is substantially accurate for approximately 95 per cent of adult human teeth, and in the manufacture of artificial dentures, a templet having this curvature is used in the articulator. As is well known by those skilled in the art, the actual angle of the setting of this plane differs with different people and also the depth of the gums of the upper and lower jaws, respectively. Furthermore, in the art of mechanical dentistry where both upper and lower dentures are to be made, one or the other is customarily complete before the making of the other, and the two are then fitted together and aligned, and in this process many separate steps, including tests and adjustments, are necessary. It is therefore desirable in an articulator that the position of the occlusal plane be carefully determined, and that thereafter, the dentures may be made utilizing the templet as much as may be necessary, and that the initial adjustments be not lost; also, it is necessary that the upper denture mechanism be separated from the lower and replaced without losing the adjustments.

It is, therefore, an object of my invention to provide an articulator having the foregoing advantages and characteristics, and one which is adjustable to all conditions that may be met in practise.

Another object is to provide in an articulator a mounting for an upper denture or templet which is removable from the base without loss of adjustments.

Other objects and advantages will appear and be brought out more fully in the following specification, reference being had to the accompanying drawings, wherein:

Fig. 1 is a plan view of an embodiment of my invention showing the occlusal plane templet.

Fig. 2 is a sectional elevation taken on the line 2—2 of Fig. 1.

Fig. 3 is an end elevation of the same.

Fig. 4 is an enlarged sectional elevation taken on the line 4—4 of Fig. 3.

Fig. 5 is a detailed view partly in section taken on the line 5—5 of Fig. 4.

Fig. 6 is a plan view of a modified form of the bracket member shown in Figs. 1 and 3.

Fig. 7 is a view similar to Fig. 2 in which the bracket shown in Fig. 6 is substituted for that of Figs. 1—3.

Fig. 8 is an elevation of the bracket member of Fig. 1 showing also the occlusal plane templet.

Fig. 9 is an enlarged sectional view taken on the line 9—9 of Fig. 8.

Fig. 10 is a separate view in sectional elevation of a modified occlusal plane templet.

Fig. 11 is a plan view partly in section of the same.

Fig. 12 is an enlarged partial section taken along the line 12—12 of Fig. 2.

Fig. 13 is a plan fragmentary view in section taken along the line 13—13 of Fig. 7.

Fig. 14 is a side elevation of further modified form of articulator.

Fig. 15 is a plan view of the same.

Fig. 16 is a front elevation of the same.

Fig. 17 is a detailed view of one of the members of the same.

Fig. 18 is a section taken along the line 18—18 of Fig. 15.

The device embodying my invention consists generally in a base to which a lower denture is to be attached, an auxiliary frame vertically adjustable with relation to the base, and a bracket hingedly mounted on the auxiliary frame and having means thereon for cooperation with the lower denture for adjusting and testing the same. These may be either in the form of a templet, preferably provided with an adjustable mounting, as illustrated in Figs. 1 to 5 and 8 to 11, or in the form of an upper denture and support as illustrated in the remaining figures of the drawings. Means are included for accurately positioning the hinged bracket and hence the testing means with relation to the lower denture.

Referring more particularly to the drawings, and especially to Figs. 1—5, I show an articulator having a base 20, an auxiliary supporting frame 21 mounted thereon to which is pivotally secured a bracket 22. Base 20 consists of a substantially T-shaped plate 23 having a pair of upstanding supporting posts 24 secured thereto by nuts 25 which also serve as feet for the partial

support of the device, plate 23 being further provided with a front end portion 26 in which is a slot 27 adapted for the attachment of an adjustable foot plate 28 which has a shank 29 provided with a square portion 30 closely fitted into slot 27, the shank having a threaded portion 31 by which a thumb nut 32 secures the plate 28 to the front end portion 27 of the base.

5 A denture mounting plate 33 is secured to the base 20 and has a threaded central aperture 34 in which is screwed a knurled lock screw 35 which passes through an aperture 36 in base 20. A centering aperture 37 is located in plate 33 and a centering stud bolt 38 passes through plate 20, 10 the head of the bolt 38 being fitted into aperture 37.

15 Supporting posts 24 are each provided with three recesses designated 39, 40, and 41, recesses 39 being at equal heights above base 20 and similarly for recesses 40 and 41 respectively for a purpose to be presently explained. Auxiliary frame 21 has a pair of side members 42 secured together by lower cross web 43 and an upper cross member 44, side members 42 being provided 20 with vertical bores 45. Each side member 42 is provided with a knurled lock screw 46, which is adapted to engage the recesses 39, 40, and 41, and, preferably at right angles thereto, a knurled lock screw 47 is provided and adapted to engage a cylindrical portion of each post 24. Cross web 43 is provided with a vertical threaded bore 48 in which a knurled adjusting screw 49 is located, a flat head screw 50 being secured in base 20 and adapted to serve as a stop for screw 49. A lock nut 51 is further provided on screw 49. The upper portions of side members 42 are each formed as a bearing head 52 and provide an open bearing 53 which has a pitched flat bearing way 54 which is preferably formed at an angle of 23 degrees with the horizontal. The upper cross member 44 is inclined or pitched at the same angle of 23 degrees and centrally thereon is a post 55 which has a threaded bore 56 likewise at the angle 23 degrees.

25 A pressure regulating screw 57 is operable in bore 56 and has a knurled head 58 and an abutment end 59 and a bore 60, which has a spring seat or abutment 61 near the front end thereof. A bearing bore 62 is formed in the front end of screw 57 and accommodates a plunger 63 which carries a bearing disc 64 at one end, the latter being urged downwardly by compression spring 65 located in bore 60. A stop collar 66 is suitably secured on the free end of plunger 63, and a lock nut 67 is operable on the threaded portion 55 of screw 57.

30 One of the main features of this invention is to provide a structure whereby the hingedly mounted bracket, after having been accurately adjusted, may be readily removed when desired and as readily replaced in exactly the original adjusted position. To this end, the bracket is provided with a pair of aligned bearings or trunnions, and the auxiliary frame is formed with forwardly and downwardly inclined ways for the trunnions, terminating in cylindrical bearings for the same; and said auxiliary frame is equipped with a spring pressed plunger for normally holding the trunnions in the bearings. Provision is also made 55 for clamping said plunger against the bracket for firmly holding the same in position when desired. To this end the pivoted bracket 22 consists of an elongated plate 68 having a pair of extension hubs 69, in each of which is a bore 70 aligned to receive a shaft 71 which is secured

therein by set screws 72. Shaft 71 is formed with reduced end bearing portions or trunnions 73 which are adapted to engage bearing 53 and bearing ways 54. Shoulders 74 are formed on shaft 71 to prevent lateral movement of the 5 same, the ends of which shaft are provided with knurled knobs 75. By this arrangement it will be seen that the shaft 74 and bracket 22 may be rotated a moderate amount laterally, using one of the bearings 53 as a fulcrum and pressing upwardly against the knurled knob 75 on the opposite end of the shaft against the pressure of spring 65. This movement is of value and importance in testing dentures, as will be apparent to those skilled in the art. It will also be apparent that bearing disc 64 may be pressed against shaft 71 with any desired pressure by appropriate adjustment of regulating screw 57 and that the same may be locked against the shaft 71 by the turning of screw 57 all the way down so that the 20 abutment end portion 59 engages disc 64. In this condition the shaft 71 is prevented from lateral movement along ways 54, but is free to rotate in both bearings 53.

25 The outer end of plate 68 is provided with a 25 downwardly depending boss 76 in which is a vertical bore 77 and a threaded lateral bore 78 (Fig. 12). A lock screw 79 engages bore 78 and an incisal pin 80 is secured thereby in the bore 77, the pin having a flattened portion 81 adapted 30 for the adjustable engagement with lock screw 79. Incisal pin 80 is graduated with a centimeter scale 82 and an ABC scale 83. The pin also has a rounded foot 84 adapted to rest on foot plate 28, and a knurled knob 85 at its upper end adapted 35 for convenience in use. Those skilled in the art will appreciate that the incisal pin 80 will be set at the A, B, or C point when the frame 42 is secured on post 24 by the lock screws 46, being set in the recesses 39, 40 and 41 respectively, 40 these positions being normally used for the majority of dentures, it being clear that if intermediate adjustments are desired the lock screws 47 will be used and the incisal pin 80 set at a selected graduation of the centimeter scale 82. 45

45 As hereinbefore stated means are carried by said hinged upper plate or bracket for cooperation with the lower denture on the occlusal plane. This in some instances is an occlusal plate templet as illustrated in Figs. 1, 2, 3, 8 and 50 9, and in some instances comprises the upper denture as shown in Figs. 6, 7, 14 and 15. Slightly modified forms of the hinged upper plate is used for these purposes. The general form of the plates are identical as is also the hinged connection to the auxiliary frame. The occlusal template plate is usually first employed in conjunction with the lower denture. Afterwards this is removed and the plate with the upper denture substituted. This is readily accomplished, as the only operation necessary to remove the one for substitution of the other is retraction of the plunger 63 and lifting the trunnions of the bracket 68 from the diagonal upwardly opening bearings. The other plate may be as readily applied, as is obvious. The only difference in the two hinged plates is in the means of attaching the respective members which cooperatively engage the lower denture. 55

60 The occlusal plate templet is secured to bracket 22 by the following described means, as shown in Figs. 1, 2, 3, 8, and 9. Bracket 22 has a spherical seated aperture 86 in which is located a spherical clamp 87, the latter having a central bore 88 and upper and lower slits 89. A 75

templet hanger rod 90 extends through bore 88 and is secured therein by a locking plate 91 having spherical seated aperture 92 which engages the upper portion of spherical clamp 87. 5 Plate 91 has apertures 93 through which extend locking screws 94, the latter being screwed into tapped apertures 95 in plate 68, the screws each having a head 96, shoulder 97, and an operating pin 98 which extends through the head 96. It should be obvious that the tightening of the screws 94 will clamp the rod 90 in any desired angular position.

In a majority of cases the lower denture is made before the upper denture and the mechanism which is described is peculiarly adapted for such a procedure. In making the upper denture, the mechanism shown in Figs. 6 and 7 is particularly advantageous, the upper bracket being shown at 22a and having elongated plate 68a to 20 which is attached a denture mounting plate 33a substantially similar to plate 33 and having a threaded central aperture 34a, a locking screw 35a extending through aperture 36a in plate 68a. A centering aperture 31a is formed in plate 33a to 25 accommodate the head of centering stud bolt 38a. Plate 33a is provided with a pair of arcuate apertures 33b to facilitate the securing of the usual plaster cast and plate 33 hereinabove described is similarly provided with arcuate apertures not shown in the drawings.

In Figs. 7, 14, 15, and 16 is shown an inclined foot plate 28a having a substantial inclination angle of 23 degrees, similar to that of the bearing ways 54.

35 In Figs. 8, 9, and 10 I show more in detail the templet support which consists of a templet rod 99 adapted to be secured to hanger rod 90 by means of a sutured clamp or clutch 100. Rod 90 has a flattened portion 101 with radial sutures 102, a tapped aperture 103 to receive the threaded portion 104 of a wing bolt 105, the templet rod 99 having a flattened portion 106 provided with radial sutures 107 and an aperture 108 to receive the bolt 105. A soft metallic disc 109, 40 preferably of aluminum, is placed between the sutures 102 and 107 by which the clamp is adjustable to any position. Templet rod 99 is preferably provided with a plurality of radially extending prongs 110 which may be secured as by welding or otherwise to the standard occlusal templet 111. If, due to an irregular denture, the standard templet is not to be used, a special or irregular templet 112 (Figs. 10 and 11) may be formed of plaster, as will be clear to those familiar with the art.

45 In Figs. 14 to 18 is shown modified means for supporting ends securing the dentures, and I show a base mounting plate 33c secured to the base 20 in a manner similar to that of plate 33, plate 33c being further provided with stop portions 113, the plate being elongated to provide for the same. Upper plate 33d, secured to plate 68a similarly to plate 33a, is provided with bosses 114, each having a bore 115, a threaded aperture 116 communicating therewith, and adapted to receive a wing bolt 117 which provides locking means for a guide rod 118 having a foot portion 119 which may engage stop portions 113 of plate 33c; the upper end of each rod 118 has a 50 knurled knob 120. Plates 33c and 33d are preferably provided with a plurality of conical bored apertures 121 to facilitate the adhesion of the plaster 122 which forms a base for the wax portion 123 of the lower denture having the occlusal plane curvature 124. In a similar manner,

plaster 125 is secured to the upper plate 33d and secures the wax portion 126 of the upper denture.

Fig. 7 shows the plaster and wax denture formations secured to plates 33 and 33a, and Fig. 2 shows the lower denture similarly secured.

The operation of my invention should be obvious from the foregoing description, it being apparent that the various features of the invention are provided with the maximum adjustability for the most efficient formation of irregular as well as standard dentures, and that the hereinabove referred to objects may be achieved by devices constructed according to this specification.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. An articulator comprising a base for a lower denture having a pair of upstanding supporting posts, an auxiliary frame mounted on said posts, a bracket provided with a pair of trunnions, 30 said frame having forwardly and downwardly inclined ways each open at the upper end and terminating at the lower end in semi-cylindrical bearings for said trunnions, retractile pressure means for yieldingly maintaining said trunnions 35 in said bearings, said means including means for locking said trunnions in said bearings, means on said bracket for cooperative engagement with the lower denture and an incisal pin adapted to position said bracket relative to said base. 40

2. An articulator comprising a base for a lower denture having a pair of upstanding supporting posts, an auxiliary frame mounted on said posts, a bracket provided with a transverse shaft terminating in trunnions, inclined ways in said supporting frame terminating in bearings for said trunnions, said adjustable frame also provided with a threaded bore positioned radially with respect to said shaft, a pressure regulating and clamping screw threaded therein, a spring 50 pressed plunger in said screw and having a bearing member adapted to engage said shaft to yieldingly hold the trunnions in said bearings, substantially as described.

3. An articulator comprising a base for a lower denture having a pair of upstanding supporting posts, an auxiliary frame mounted on said posts, a bracket provided with a transverse shaft terminating in trunnions, inclined ways in said supporting frame terminating in bearings for 60 said trunnions, said adjustable frame also provided with a threaded bore positioned radially with respect to said shaft, a pressure regulating and clamping screw threaded therein, a spring 65 pressed plunger in said screw and having a bearing member adapted to engage said shaft to yieldingly hold the trunnions in said bearings, and said clamping screw adapted to be adjusted to impinge against the bearing member on the plunger as and for the purpose specified. 70

4. An articulator comprising a base for a lower denture having a pair of upstanding supporting posts each provided with a plurality of recesses, an auxiliary frame mounted on said posts, set screws engageable with the recesses in said posts 75

- for securing the frame in predetermined vertical position, a bracket provided with a transverse shaft terminating in trunnions, inclined ways in said supporting frame terminating in bearings 5 for said trunnions, said adjustable frame also provided with a threaded bore positioned radially with respect to said shaft, a pressure regulating and clamping screw threaded therein, a spring pressed plunger in said screw and having a bearing member adapted to engage said shaft to 10 yieldingly hold the trunnions in said bearings, and said clamping screw adapted to be adjusted to impinge against the bearing member on the plunger as and for the purpose specified.
- 15 5. An articulator as described comprising a base for a lower denture having a pair of up-standing supporting posts, an auxiliary supporting frame on said posts, a bracket for an upper denture having a pivotal connection with said frame, said connection including bearings in said frame radially open at one side thereof, a shaft in said bearings, means for retaining said shaft in said bearings said means including a spring biased bearing disc and a locking sleeve therefor, an incisal pin adapted to adjustably position 20 said bracket in relation to said base.
- 25 6. An articulator as described comprising a base for a lower denture having a pair of up-standing supporting posts, an auxiliary supporting frame on said posts, a bracket pivotally mounted on said frame, a templet hanger rod mounted for universal adjustment on said bracket and having a plurality of laterally extending prongs

at the lower end thereof, and an incisal pin adapted to adjustably position said bracket in relation to said base.

7. An articulator as described comprising a base for a lower denture having a pair of up-standing supporting posts, an auxiliary supporting frame on said posts, a bracket pivotally mounted on said frame, a templet hanger rod adjustably secured to said bracket and having a jointed portion and a plurality of laterally extending 10 prongs at the lower end thereof, and an incisal pin adapted to adjustably position said bracket in relation to said base.

8. An articulator comprising a base for a lower denture having a pair of upstanding supporting posts, an auxiliary frame mounted on said posts, a bracket comprising an elongated plate having a pair of spaced hubs in longitudinal alignment, a shaft adjustably mounted in said hubs, means for securing said hubs and shaft in 15 fixed relation, trunnions on the ends of said shaft, inclined ways in said supporting frame terminating in bearings for said trunnions, said adjustable frame also provided with a threaded bore positioned radially with respect to said 20 shaft, a pressure regulating clamping screw threaded therein, a spring pressed plunger in said screw and having a bearing member adapted to engage said shaft between said hubs to 25 yieldingly hold the trunnions in said bearings, substantially as described.

EDWARD L. CHOTT.
